(57) **CLAIM**

The ornamental design for the LED light bulb, as shown and
described.

DESCRIPTION

FIG. 1 is an isometric view of an LED light bulb in accordance
with a preferred embodiment of my design;

FIG. 2 is a front view of the LED light bulb of FIG. 1, the rear
view being a mirror image thereof;

FIG. 3 is a left side view of the LED light bulb of FIG. 1, the
right side being a mirror image thereof;

FIG. 4 is a top view of the LED light bulb of FIG. 1; and,
FIG. 5 is a bottom view of the LED light bulb of FIG. 1.
The dashed lines shown in the figures represent environmental
subject matter and form no part of the claimed design.
